UNITED STATES PATENT OFFICE.

JULIUS SCHREIBER, OF LINCOLN, ILLINOIS

LIFE-PRESERVER.

1,150,460.

Specification of Letters Patent. Patented Aug. 17, 1915.

Application filed September 28, 1914. Serial No. 864,007.

To all whom it may concern:

Be it known that I, JULIUS SCHREIBER, a citizen of the United States, residing at Lincoln, in the county of Logan, in the State of Illinois, have invented certain new and useful Improvements in Life-Preservers, of which the following is a specification:

This invention relates to new and useful improvements in life preservers generally, and relates particularly to helmets designed to inclose the head of the wearer to form a protection when under water, said helmet being provided with an air supply by means of which the wearer is free to inhale and exhale in comparatively normal manner.

With the above and other objects in view, this invention consists in construction of a combination and arrangement of parts, all as hereinafter more fully described, claimed, and illustrated in the accompanying drawing, wherein:

Figure 1 is a vertical section through the helmet constructed in accordance with the present invention illustrating the same in use; Fig. 2 is a front elevation thereof; Fig. 3 is a horizontal section along the line 3, of Fig. 1 and illustrates the valve mechanism whereby the wearer may inhale and exhale while under water; and Fig. 4 is a top plan view thereof.

Reference being had more particularly to the drawing, it will be apparent that the present invention is used in conjunction with an ordinary life preserver P which encircles the body of the wearer, while under water, and comprises a helmet 10, having a partition 11 in the upper end thereof to form an air reservoir R, said reservoir being entirely operated from the body of the helmet into which the head of the wearer projects, except by means of the air conduit to be described. The front side of the helmet is provided with the lips 12 which surround the side opening 12, said side opening being closed by a section of plate glass 13 which permits the wearer to observe on the exterior of the helmet. The lower end of the helmet is opened to a sufficient size to permit of the entrance of an average sized head, and is somewhat contracted on the forward side as at 14. An elastic band 15 of rubber or other waterproof material is secured to the lower end of the helmet and is illustrated in Fig. 1, also designed to closely embrace the neck 1 of the wearer to prevent the entrance of

water into the body of the helmet below the partition 11.

In order to provide means of conducting air from the reservoir R to the wearer, a supply pipe 16 extends from the reservoir R to a point approximately on the plane of the mouth of the wearer where it terminates and is secured to one extremity of a valve casing 17. The opposite extremity of the valve casing 17 connects with an exhaust pipe 18 which pierces the wall of the helmet 10 and terminates upon the exterior thereof. A seat 19 is centrally formed upon the valve casing 17 and has a mouthpiece 20 secured thereto by means of which the wearer is enabled to extract air from the reservoir R and exhale through the exhaust pipe 18. The end of the casing 17 adjacent to the supply pipe 16 is provided with a gate valve 21 which operates to open when the air is extracted through supply pipe 16 from the reservoir R; whereas the opposite end of the casing 17 is provided with an aperture partition 22 upon the outer side of which is a gate valve 23, arranged to open when air is forced into the casing by the exhaling of the wearer, which action closes the valve 21 and permits the air to escape through the exhaust pipe 18. When the wearer is inhaling or extracting air from the reservoir R, such action will close the valve 23 by creating a suction in the chamber between said valves.

In order to provide a means whereby air may be supplied to the reservoir R and at the same time close said reservoir R when the helmet is under water, a cylinder 24 is formed on the rear side of the helmet and is provided at its upper terminal with an air opening 25 communicating with the interior of the cylinder 24. This cylinder, as illustrated in Fig. 1, connects with the air reservoir R. Suitable bearings 26 are formed or mounted within this cylinder and vertically aligned for the reception of the valve rod 27 which carries its upper terminal, the valve 28 being arranged to close the air opening 25. The lower terminal of the rod 27 passes through an aperture partition 29, the aperture of which is arranged to be closed by a valve 30 mounted on the rod 27 below said partition. In order to reciprocate the rod 27 to close both the air opening 25 and the aperture partition 29, the lower terminal casing is perforated as at 31 by means of which water

may enter the lower end of the cylinder and the helmet is submerged and operates against a float 32 secured to the extreme lower end of the rod 27.

- 5 It will be apparent that when the helmet is not submerged gravity will cause the rod 27 and the elements carried thereby to move downwardly and remain in such a position, thus permitting air to enter through the 10 opening 25, enter the cylinder 24, and from there into the reservoir R. Upon the submersion of the helmet, the water in the perforation 31 operates against the float 32, causing the rod 27 to move upwardly and 15 seat the valves 28 and 30 against their co-operating apertures, shutting off communications between the reservoir R and the water, permitting the air stores in said reservoir to be extracted by the wearer.
- 20 In order to hold the helmet in place, the sides thereof are provided with straps 33 of a suitable construction, size, and shape, which are designed to be secured in any desired manner to the body of the wearer.
- 25 While the preferred form of the present invention has been illustrated and described, it is to be understood that many changes in the details of construction can be made without departing from the spirit and scope 30 hereof.

I claim as my invention:

1. The combination with a helmet having an air reservoir therein, of means for supplying air thereto comprising a cylinder 35 communicating with said reservoir, having

an air inlet, and means operable by the action of water for closing said inlet when the helmet is submerged.

2. The combination with a helmet, of a partition therein, forming an air reservoir, 40 an air supply pipe leading from the reservoir to the body of the helmet, a valve casing with one end of which the supply pipe connects, a partition in said casing, a mouth piece communication with said casing between said partition and said supply pipe, an exhaust pipe connected to the opposite end of the casing to the supply pipe, and valves mounted in the casing adjacent to the partition and intake or supply pipe for 45 operation by respiration through the mouth-piece aforesaid.

3. The combination with a helmet, of a partition therein forming an air reservoir, 55 means for conducting air from the reservoir to the body of the helmet, means for exhausting air so conducted to the reservoir, both of said means being operable alternately by respiration of the wearer, air supply means for the reservoir aforesaid and means for automatically rendering said air supply means inoperative when the helmet is submerged.

In testimony whereof I have hereunto of-
fixed my name in the presence of two wit-
nesses.

JULIUS SCHREIBER.
